SEPARATING AND EXTRACTING
APPARATUS

Harry B. Ross, Denver, Colo.

Application January 9, 1933, Serial No. 650,841

2 Claims. (Cl. 209—185)

This invention relates to classifying, separating and extracting apparatus and has as an object the provision of an improved unitary apparatus operable to divide an admixture of comminuted ingredients normally insoluble in water into groups marked by a difference in specific gravities.

5 A further object of the invention is to provide an improved unitary apparatus particularly adapted to separate gold and other heavy metals from sands and ore pulps.

10 A further object of the invention is to provide an improved unitary apparatus operable in combination with a precipitating agent to separate 15 certain solutions of gold and other heavy metals from sands and ore pulps.

15 A further object of the invention is to provide an improved unitary apparatus susceptible of rapid and efficient operation as an amalgamator 20 for the extraction of gold from sands and ore pulps.

25 A further object of the invention is to provide an improved unitary apparatus operable as a diaphragm to retain metals of specific gravities greater than those of gangues.

30 A further object of the invention is to provide an improved unitary apparatus operable to indicate losses of heavy metals escaping from 35 separatory apparatus of conventional type.

35 A further object of the invention is to provide an improved classifying, separating and extracting apparatus which is simple and inexpensive of manufacture, installation and operation, rapid and efficient in operation, susceptible of infinite variation in capacity, and adapted for use either independently or in combination with other related apparatus.

40 My invention consists in the construction, arrangement and combination of elements hereinafter set forth, pointed out in my claims and illustrated by the accompanying drawing, in which—

45 Figure 1 is a side elevation of one embodiment of my invention as arranged and positioned for practical use. Figure 2 is a plain view of the showing of Figure 1. Figure 3 is a vertical section taken axially of a slightly modified form of the arrangement shown in Figures 1 and 2. Figure 4 is a vertical section, on a reduced scale, 50 taken axially of a further modified form of the invention.

The apparatus hereinafter described is particularly adapted for and efficient in the recovery of uncombined gold and certain solutions of combined gold, from placer sands and ore pulps, and

its operation will be described in connection with such specific application, but it is to be understood that such application is in no sense limitative, since the principle whereon the apparatus operates adapts it for use as a classifier, separator and extractor in a number of otherwise unrelated fields.

In the extraction of uncombined gold from placer sands, heavy, black sands will frequently be encountered, which heavy sands act to destroy the efficiency of conventional sluices, riffles and amalgamating tables by retarding, and in some instances preventing, the gravitational action on the gold particles which is the essential principle of conventional processes. Further, it is found that many placer sands, and some ore pulps, carry gold particles so fine, of such shape and in such soluble combination, that they do not respond to gravitational attraction sufficiently for extraction by conventional processes, the buoyant surface tension effect of the liquid vehicle employed or the displacement by the bulkier heavy sands frequently resulting in so inefficient an extraction that conventional processes cannot be profitably employed in treating sands and pulps showing normally profitable assays. The instant invention has been designed to overcome the foregoing difficulties and, for reasons which will appear hereinafter, can be employed to efficiently and economically extract the values from all sands and ore pulps carrying free gold and from most sands and ore pulps carrying soluble compounds of gold.

In the construction of the improved apparatus as shown, the numeral 10 designates a receiver or bowl, preferably of inverted frusto-conical form, formed of any suitable material in any desired manner, and preferably provided with means, such as adjustable legs 11, whereby the receiver may be leveled relative to its supporting surface. The bottom of the receiver may be plane, but is preferably formed with a concentric, upwardly-extending dome 12, the walls of which are spaced inwardly somewhat from the walls of the receiver 10 to form an annular trough in the lower portion of the receiver. A suction head 13, preferably frusto-conical in form and formed with smooth inner walls in any desired manner from any suitable material, has a diameter at its greater end sufficient to permit of the dome 12 being telescopedically received in spaced relation within the suction head 13, in the manner shown in Figure 3, the suction head 13 being supported in any suitable manner within and in concentric relation with the receiver 10 and preferably ar-

ranged for adjustable spacing of its lower margin relative to the floor of the annular trough formed in said receiver, adjustable legs 14 carried by the suction head 13 in position to bear against the 5 floor of said annular trough being shown as one convenient means for leveling and adjusting the spacing of the suction head relative to the receiver. A suitable pipe 15 communicates with and leads from the lesser end of the suction head 10 and is preferably provided with a suitable control valve 16, the pipe 15 being extended to operative connection with suitable suction-generating means, such as a pump, jet, or siphon extension, whereby suction effect may be applied to act 15 through the open end of the suction head 13 within the receiver 10.

The material to be acted upon by the apparatus is screened, ground and/or otherwise treated to bring it to the desired degree of comminution 20 and is mixed with an excess of water prior to its introduction into the apparatus, which introduction may be effected in any suitable manner, it being desirable only that the feed to the receiver be relatively uniform and so arranged as to uniformly distribute the material in the receiver. 25 As shown in Figures 1 and 2, a sluice or flume 17 may be provided to bring the material to the receiver, in which case it is desirable that the sluice or flume be arranged to discharge tangentially within the receiver in order to maintain a circular flow within the latter whereby a substantially uniform distribution of the material is had. 30 In Figure 3 is shown a modified feeding arrangement in which a pipe 18 is illustrated as the discharge end of the material-feeding means, which pipe 18 is positioned axially of the apparatus and arranged to effect its discharge circumferentially of and against the lesser end of the suction head 13, the sloping walls of the latter maintaining a 35 relatively uniform distribution of the material discharged thereon. In the modification according to Figure 4, a vertically-adjustable, annular baffle 21 is arranged concentrically within the receiver 10 with its lower margin in slightly spaced 40 relation with the inner sloping wall of said receiver, thus forming a V-shaped trough having a circumferential gravity outlet through which the material may be fed to the suction head 13, the material-feeding means 20 in this modification 45 preferably discharging tangentially of the receiver and within the V-shaped trough where a circular flow is thus maintained to insure uniform feeding from the V-shaped trough, the adjustable feature of the baffle 19 providing means for regulating the rate of feed beneath said baffle. 50 It is of course obvious that ribs may be formed on the outer surface of the head 13 to enhance the uniformity of material distribution, or that the entire head 13 may be mounted for rotation 55 about its axis and arranged to be rotatively driven, either by spiral vanes to be acted upon by incoming material flow or by an independent source of power, all such modifications having as an object to maintain uniform distribution of 60 material within the receiver and hence being properly comprised within the scope of the instant invention.

The apparatus assembled as shown and thus far described is complete and ready for operation 65 as a classifier, separator and/or extractor with respect to mixtures of certain types. When so employed, material is introduced by continuous flow into the receiver 10 and permitted to rise in said receiver until the mouth of the suction head is covered to a considerable depth, where-

upon suction is applied through the pipe 15 to the suction head 13 and acts to draw the liquid vehicle and certain of the lighter ingredients of the mixture from the receiver and through the pipe 15 for such discharge to other apparatus or such other disposal as may be desired, leaving the heavier ingredients of the mixture in the annular trough of the apparatus, whence they may be salvaged through a suitable clean-out port 19 when a given run of the apparatus has been completed. The force of the suction effect may be varied to suit the material being treated, it being obvious that a greater suction force will exhaust heavier particles than will a lesser such force. Also, the rate of exhaustion from the receiver may be controlled by the valve 16 and should be so adjusted relative to the inflow as to maintain an adequate depth of liquid and material over the mouth of the suction head at all times.

When the apparatus is to be employed in extracting gold from placer sands and ore pulps, the material to be treated is prepared, mixed with an excess of water and introduced into the receiver as above described. Prior to operation of the apparatus, a quantity of mercury is placed in the annular trough of the receiver in amount sufficient to seal the open mouth of the suction head, even when the suction force has raised the mercury level within said head and depressed the said level without said head, as indicated by the dotted lines in Figure 3. With the mercury trap formed as above described, the suction force is adjusted to that which falls just short of "flouring" or pulling through the mercury, which force is adequate to draw through the mercury bath all sands, including the heavy black sands, and all other particles save those of the metals having specific gravities greater than that of mercury. Large particles of gold will readily separate from the mixture and remain at the bottom of the annular trough, while the finer particles, by virtue of the long intimate contact with the mercury while passing through the bath, will be rubbed free of any adverse film or coating and hence readily amalgamate and be thus held in the bath, it being found in practice that few values escape the mercury trap when the apparatus is properly adjusted and operated. The depth of the mercury bath should be sufficient to adequately seal the mouth of the suction head at all times, thus holding the values in their travel through the bath in contact with the mercury for a relatively long time and preventing attrition of the mercury through distribution of the pulp over and through relatively large volumes of said mercury. The mercury may be treated with a precipitating agent, or such agent may be added to the mixture prior to its introduction into the receiver when pulps containing soluble salts of gold are being treated, the precipitating agent acting to release the gold for entrapment and/or amalgamation as above described. Certain sands or ores may carry their own precipitating agents in a natural state, in which case the thorough, intimate mixing given the pulp in its travel through the apparatus insures release of those values which might otherwise escape recovery. The apparatus may be operated until the mercury is substantially saturated with gold values, when the operation may be halted to permit substitution of fresh mercury or removal of the value-bearing mercury for ultimate recovery of the values and replacement of the mercury. To prevent zones of lesser resistance wherealong

some values might escape, it has been found advantageous in certain instances to provide those portions of the suction head and receiver with which the mercury bath is in contact with a suitably deposited mercury coating, thus insuring good contact between the mercury bath and the structural elements of the apparatus.

It is to be noted that a functional advantage deriving from the arrangement hereabove described is found in the complete exclusion of air from the mercury trap, which air, when permitted to pass through the trap, acts to "flour" the mercury at relatively low pressures and also envelops particles of the values sought to be recovered, thereby enhancing the difficulty of their extraction. With the suction action described, air will not be drawn through the trap until all of the liquid has passed therethrough, while with pressure types of functionally similar apparatus the air is of necessity forced through the diaphragm with or in advance of the liquid vehicle employed.

In the modification of the apparatus shown in Figure 4, in addition to the features previously described, it is to be noted that the dome 12 has been replaced by a flatter, conical dome 12', the latter permitting the use of a greater volume of mercury and avoiding any constriction of passage as the mercury is elevated within the suction head. Also, the suction head 13 has been replaced by an equivalent 13', the latter being longer and more slowly tapered than the former and being provided with an extension 15' of the pipe 15 within the head and approaching the level of the mercury bath, a more effective suction being had in some instances with the modified construction shown. The pipe 15 is extended to connection with a preferably flexible gravity siphon 15", the flexible character of the latter permitting ready adjustment of the suction force acting within the head 13'. To aid in establishing flow through the siphon, a valve or valves 22 may be provided in the upper portion of the head 13' wherethrough air may enter the suction head.

Since many changes in the specific form, construction and arrangement of the elements shown and described may be had without departing from the spirit of the invention, I wish to be understood as being limited solely by the scope of the appended claims rather than by any details of the illustrative showing and foregoing description.

I claim as my invention—

1. Apparatus operable to separate a comminuted mixture in a liquid medium into groups of ingredients marked by differences in specific gravities and comprising an inverted frusto-conical receiver having a base formed with an upwardly-extended central portion cooperating with the side walls of the receiver to form a relatively narrow annular trough, a conical suction head formed with an open lower end adapted to loosely telescope over said upwardly-extended base portion and be received in said annular trough, means for continuously feeding said mixture and medium to said receiver, a suction pipe communicating with said suction head and control means in said pipe whereby the suction effect acting through said head may be adjusted to maintain a depth of mixture and medium in said annular trough sufficient to close the mouth of said suction head.

2. Apparatus operable to extract gold from comminuted sands and ore pulps in a liquid medium and comprising an inverted frusto-conical receiver formed with a central dome rising from its base to define a relatively narrow annular trough, a frusto-conical suction head in loosely telescoping relation with said dome and opening into said trough, a mercury bath in said trough and sealing the mouth of said suction head to form a trap, means for continuously feeding material to be treated to said receiver, a suction pipe communicating with said suction head and control means for said pipe whereby the suction effect acting through said suction head may be limited to act only on materials having specific gravities less than that of mercury.
